UNITED STATES PATENT OFFICE.

HORACE G. DODDS, OF NEW CASTLE, PENNSYLVANIA, ASSIGNOR OF ONE-HALF TO HENRY EARL BEIGHLER, OF SAME PLACE.

NON-REFILLABLE BOTTLE.

SPECIFICATION forming part of Letters Patent No. 609,736, dated August 23, 1898.

Application filed April 12, 1898. Serial No. 677,803. (No model.)

To all whom it may concern:

Be it known that I, HORACE G. DODDS, a citizen of the United States, residing at New Castle, in the county of Lawrence and State 5 of Pennsylvania, have invented certain new and useful Improvements in Non-Refillable Bottles; and I do declare the following to be a full, clear, and exact description of the invention, such as will enable others skilled in 10 the art to which it appertains to make and use the same, reference being had to the accompanying drawings, and to the figures of reference marked thereon, which form a part of this specification.

15 My invention relates to a new and useful improvement in non-refillable bottles, and has for its object to provide a novel and effective stopper to prevent the bottle from being refilled.

20 The invention aims to construct a non-refillable bottle having an enlarged neck, the enlargement having two apartments, the one larger and above the other, the lower one to receive a stopper-disk or auxiliary stopper 25 and the upper a guard plate or disk, so arranged and adjusted that when the bottle has once been filled and the contents removed the bottle cannot be filled again, and particularly so that if the bottle was laid upon its side or 30 effort made to refill the same by centrifugal force or by exhausting the air therefrom the inward flow of the liquid would strike the top of the base of the auxiliary stopper and force it against its seat and close communication 35 to the bottle.

The invention particularly relates to an improvement upon Letters Patent granted to H. E. Beighler December 21, 1897, No. 596,011.

In describing the invention in detail reference is had to the accompanying drawings, which form part of this specification, and wherein like figures of reference denote corresponding descriptive parts throughout the several views, in which—

45 Figure 1 is a vertical sectional view of the neck of the bottle on the line A B, Fig. 2, with all the parts in position and the bottle ready for filling. Fig. 2 is a sectional plan view on the line C D, Fig. 1. Fig. 3 is a vertical sectional view on the line E F, Fig. 2.

Fig. 4 is a top view of the guard plate or disk. Fig. 5 is a top view of the auxiliary stopper.

The upper enlarged portion of the neck of the bottle is made the proper size to form chamber or apartment 15 for guard-plate 4 to rest in and wide enough at the shoulders 18 to admit stopper-disk 20 to pass through into the enlarged portion of the neck 14. The auxiliary stopper 20 has at its lower end a circular plate or disk with indented edges, a 60 standard 19 running upward into an upper circular plate or disk 2 and preferably made of glass, the upper and lower plates or disks being so made as to play neatly in apartment 14 and the upper plate serving to keep the 65 said auxiliary stopper in an upright position. Guard-plate 4 has an annular rim or ridge 12 running into guide-posts 8 on the upper side of said guard-plate. The guide-posts 8 of disk 4, bearing against the upper wall of 70 apartment 15, serve to hold disk 4 firmly in position upon shoulders 18 on guides 7. The guides 7 extend from the upper part of corresponding guide-posts 8 of disk 4 down to a point in apartment 14 above the top of the 75 lower plate of auxiliary stopper 20 when suspended instead of below the stopper, as in the Beighlee patent, and prevent the auxiliary stopper from attaining any side motion. On each side of guides 7 are the vertical channels 5, which connect the narrow portion of the neck 10 with the lower enlarged portion of the neck 14, ending at a point above the top of lower plate of the auxiliary stopper 20 80 when suspended, and thus the liquid, passing 85 inward through apartment 14, first falls upon the lower plate of auxiliary stopper 20 and must pass through the indentations on its edge on its way into the body of the bottle. The wire 3 is bent inward and upward at its 90 ends 11 and hooked under the upper circular plate of stopper-disk 20 and passes through channels 5 and over and rests upon annular rim 12 of guard-disk 4.

The operation is as follows: The neck of 95 the bottle is originally blown in the shape as indicated at 1 and as shown in dotted lines in Fig. 1. The auxiliary stopper and guard-disk are then fastened together by means of the wire and the same lowered into the neck of 100

the bottle with the guard-plate resting on the shoulder or seat 18. The upper part of the neck is then reduced to its proper size, and the bottle is ready for filling, the liquid passing through said channels, the lower enlarged portion of the neck, and through said indentations into the body of the bottle. When the bottle is filled, the wire is withdrawn by a hook or other instrument, whereupon the auxiliary stopper is released and permitted to descend to its seat or shoulder 17, thus closing communication with the body of the bottle. The bottle may be corked or sealed in the ordinary way.

15 Having thus described my invention, what I desire to secure by Letters Patent is—

1. In a non-refillable bottle, a bottle-neck having an upper and lower enlarged portion one above the other, short vertical channels connecting the two portions, the upper portion having at its base a shoulder or seat to receive a guard-plate, an annular rim or ridge on said guard-plate; and said lower portion having at its base a shoulder or seat auxiliary movable stopper with solid indented base which is confined below said channels, a standard and disk, substantially as herein shown and described.
2. In a non-refillable bottle, a neck, said neck having an upper and lower enlarged portion, a seat at the lower end of said upper enlarged portion adapted to have seated thereon a guard-plate, a movable auxiliary indented stopper, said stopper adapted to be seated upon a shoulder formed at lower end of said lower enlarged portion and channels above the limit of movement of said stopper, substantially as herein shown and described.
3. In a non-refillable bottle, a neck, said neck having an upper and lower enlarged portion, vertical channels connecting the two portions for the admission of the liquid to the bottle, said enlarged portions having shoulders or seats at their lower ends, a guard-plate arranged in said upper portion, a movable auxiliary stopper having a solid indented

base which is confined below said channel, a standard and disk, and said auxiliary stopper arranged in said lower enlarged portion, and adapted to be suspended by means of a wire 50 passing through said channels and over and resting upon said guard-plate, said wire fastened to the under side of said stopper-disk, said auxiliary stopper adapted to be seated upon the seat or shoulder of said lower enlarged portion when the wire is withdrawn, substantially as herein shown and described.

4. In a non-refillable bottle, the combination of a neck having two enlarged portions one above the other and connected by short 60 channels, a guard-plate arranged in said upper enlarged portion of the neck, seated against a shoulder or seat formed at the lower end of said upper enlarged portion, said guard-plate having an annular rim or ridge, 65 a stopper-disk connected to a movable auxiliary stopper by a standard, said auxiliary stopper having a solid indented or scalloped base which is confined below said channels and arranged within said lower enlarged neck 70 portion, said lower enlarged neck portion having a shoulder at its lower end, a wire connecting said guard-plate, stopper-disk and auxiliary stopper, said auxiliary stopper adapted to be seated against a shoulder or 75 seat at the lower end of the lower enlarged neck portion when the wire is withdrawn, substantially as herein shown and described.

5. In a non-refillable bottle, a neck provided with a guard, channels around said guard, a movable valve provided with an indented base, a valve-seat, and a cylindrical portion above said seat, the upward limit of movement of said base being always below said channels, substantially as described. 80

In testimony whereof I affix my signature in presence of two witnesses.

HORACE G. DODDS.
